Ward, Crosby & Smith

UNITED STATES PATENT OFFICE.

FRANKLIN C. LEWIS, OF NEW YORK, N. Y.

NECKTIE ATTACHMENT.

Application filed April 6, 1925. Serial No. 20,887.

To all whom it may concern:

Be it known that I, FRANKLIN C. LEWIS, a citizen of the United States, and resident of New York, county of New York, and 5 State of New York, have invented certain new and useful Improvements in Necktie Attachments, of which the following is a specification.

My invention relates to improvements in 10 necktie attachments and more particularly to attachments for use in connection with so-called four-in-hand neckties. The main object of the invention is to provide a simple and efficient device to prevent such 15 ties from jamming or sticking when worn with turn-over collars. A further object of the invention is to provide a device which will hold the tie near the bottom of a turn-over collar, especially at the back 20 thereof whereby the tie will not become pinched in the top of the collar. A further object of the invention is to protect the tie from the rear collar button.

Further and more specific objects, features and advantages will more clearly appear from the detail description given below taken in connection with the accompanying drawings which form a part of this 25 specification. In the drawings Fig. 1 is a 30 perspective showing a device embodying my improvements in a preferred form thereof, inserted in a collar with a tie, part of the collar being broken away. Fig. 2 is an elevation of the device. Fig. 3 is a 35 cross section of the same taken either on the line *a—a* or the line *b—b* of Fig. 2 and also showing a portion of the collar and rear collar button.

Referring to the drawings, 4 represents 40 the body portion of the device which is preferably made out of sheet metal. Extending upwardly from the upper corners of the body portion 4 are two projecting tabs 5 and 6. 7 represents a lip or bent over portion, bent down from the top edge 45 of the body portion 4, and 8 represents a lip or bent over portion bent up from the bottom edge of the body portion 4. After the portions 7 and 8 are bent over they are 50 spaced from the body portion 4 as shown in Fig. 3, thus providing a slideway between the lips 7 and 8 on one side and the body portion 4 on the other side, through which the necktie 2 is adapted to be placed 55 and slide. The four-in-hand tie 2 after being placed in the slideway between the

portions 7 and 8 on one side and the body portion 4 on the other side, is pulled therethrough so that the device comes at the central part of the tie where it will be adjacent the back collar button when the tie is placed in a turn-over collar. The tie with the device is then placed in the collar between the inside fold 3 and the outside fold 3' thereof as illustrated in Fig. 3 and 60 with the body portion 4 bearing against the rear collar button 1. The tabs 5 and 6 project up to the top of the collar between the folds thereof and serve to keep the tie, which is held in the lower part of the device, at the bottom part of the collar. It will be noted that the body portion 4 and lips 7 and 8 are slightly curved to conform 65 to the general lines of the collar and neck.

It will be seen from the above that the 70 device provides means forming a slideway between the portions 7 and 8 on one side and the body portion 4 on the other side through which the tie may slide easily so that it may be easily tied and also easily 75 untied at the front, and so that the tie is prevented from jamming or sticking between the folds of the collar at the back. Likewise the tie is protected from the rear 80 collar button which would otherwise tend to prevent the tie from slipping freely between the folds of the collar. It will be understood that the tabs 5 and 6 as well as the bent-over portions 7 and 8 are integral 85 with the body portion but so that the whole 90 device is made of one piece.

While I have described my improvements in great detail and with respect to a preferred form thereof, I do not desire to be limited 95 to such form or details since many changes and modifications may be made and the invention embodied in widely different forms without departing from the spirit and scope thereof in its broader aspects. Hence I desire to cover all modifications and forms 100 coming within the language or scope of any one or more of the appended claims.

What I claim as new and desire to secure by Letters Patent is:

1. A necktie attachment comprising a 105 body portion provided with a horizontal guideway at the bottom part thereof in which the tie is adapted to be placed and through which the tie is adapted to slide and also provided with means extending 110 upwardly therefrom and adapted to space the said guideway from the top edge of a

turn-over collar, said guideway being formed by an integral lip extending downwardly from the top of the body portion, and an integral lip extending upwardly from the bottom of the body portion.

2. A necktie attachment comprising a body portion having at the bottom part thereof, a guideway in which the necktie is adapted to be placed and slide horizontally, said body portion being provided with a

plurality of upwardly extending portions adapted to hold the guideway toward the bottom of a turn-over collar, and said guideway being formed of a lip extending downwardly from the upper part of the bottom portion and a lip extending upwardly from the lower part of the body portion.

In testimony whereof I have signed my name to this specification.

FRANKLIN C. LEWIS.
